(57) **CLAIM**

The ornamental design for an adjustable elastic binding rope, as shown and described.

DESCRIPTION

FIG. 1 is a front, right, and top perspective view of an adjustable elastic binding rope, showing my design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a first side of a head part of the adjustable elastic binding rope of FIG. 1; and,

FIG. 10 is a partial enlarged view of an area labeled 10 in FIG. 2 comprising a second side of the head part of the adjustable elastic binding rope of FIG. 1.

The adjustable elastic binding rope is shown with a symbolic break in the length of the design in FIG. 1-6. The appearance of any portion of the article between the break lines forms no part of the claimed design.
